(57) **CLAIM**

The ornamental design for a tubular noodle fishing float with
visibility marker holders, as shown and described.

DESCRIPTION

FIG. 1 is a perspective view of the tubular noodle fishing float
with visibility marker holders, in which the holders extend
from a band or cap that is placed around the tubular portion of
the float;

FIG. 2 is a front view thereof; and,

FIG. 3 is a side view thereof.

The broken line showing of environment in the drawings is
included for the purpose of illustrating only and forms no part
of the claimed design.
